(57) **CLAIM**

I claim the ornamental design for the thermoformed fence section, as shown and described.

DESCRIPTION

FIG. 1 is a top plan view of a thermoformed fence section; FIG. 2 is a front elevational view of the thermoformed fence section;

FIG. 3 is a left side elevational view of the thermoformed fence section;

FIG. 4 is a right side elevational view of the thermoformed fence section;

FIG. 5 is a bottom plan view of the thermoformed fence section;

FIG. 6 is a front perspective view of the thermoformed fence section; and,

FIG. 7 is a rear perspective view of the thermoformed fence section.

1 Claim, 2 Drawing Sheets

*FIG. 1**FIG. 3**FIG. 2**FIG. 4**FIG. 5**FIG. 6*

FIG. 7
